(57) **CLAIM**

The ornamental design for the geometric modelling element, as shown and described.

DESCRIPTION

FIG. 1 is a plan view showing my new design for a geometric modeling element; and,

FIG. 2 is a plan view showing a second embodiment of my new design including a central hole.

In each embodiment, the opposing plan views are mirror images of one another; and the thickness minimal.

1 Claim, 1 Drawing Sheet**FIG. 1**

FIG. 2
